(57) **CLAIM**

The ornamental design for a jig head, as shown and described.

DESCRIPTION

FIG. 1 is a front view of a jig head showing the claimed design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a top left perspective view thereof; and,

FIG. 8 is top left perspective view of a jig head showing the claimed design in an environment in which it may be used. The dashed broken lines in the figures show portions of the jig head subject matter that form no part of the claimed design. The separation and bracket in the figures indicate that the precise length of the flashing of the jig head is not claimed, and the appearance of any portion of the article between the break lines forms no part of the claimed design. The embodiment of FIGS. 1-7 differs from the embodiment of FIG. 8 only in regards to the skirt and soft artificial bait, which form no part of the claimed design.
